DESIGN FOR A LADY'S GLOVE

Edith Margaret Screaten, New York, N. Y.

Application November 2, 1934, Serial No. 53,851

Term of patent 3½ years

To all whom it may concern:

Be it known that I, Edith Margaret Screaten, a subject of the Dominion of Canada, residing in Manhattan, in the county of New York and State of New York, have invented the new, original, and ornamental Design for a Lady's Glove, of which the following is a specification, reference being had to the accompanying drawing, forming part thereof, wherein,

Figure 1 is a front view of a glove, showing my new design.

Figure 2 is a rear view of the glove, shown in Figure 1.

The characteristic feature of my design resides in the application of an initial to the wrist band of a glove.

I claim:

The ornamental design for a lady's glove, substantially as shown and described.

EDITH MARGARET SCREATEN.
